Specification for Design.

Patented Dec. 14, 1920.

Application filed July 10, 1920. Serial No. 395,393. Term of patent 14 years.

To all whom it may concern:

Be it known that I, ARTHUR W. WADSWORTH, a citizen of the United States, residing at Fort Thomas, in the county of Campbell, and in the State of Kentucky, have invented a new, original, and ornamental Design for a Watchcase-Crown, of which the following is a specification, reference being had to the accompanying drawing, forming part thereof.

In the drawing:

Figure 1 is a side elevation of a watch-

case crown embodying my design, its relation to the bow, pendant and case being indicated by dotted lines; and

Fig. 2 is a top view of the crown.

I claim:

The ornamental design for a watchcase crown, substantially as shown.

ARTHUR W. WADSWORTH.
